UNITED STATES PATENT OFFICE.

ALFRED W. SCHULTZ, OF WATERLOO, IOWA.

PIPE-FORMING MACHINE.

Application filed April 18, 1928. Serial No. 270,897.

This invention relates to means for making pipe from moldable material such as concrete or cement and particularly to means for forming pipe sections having flaring or bell-shaped ends adapted to receive the ends of other sections.

It is old to form pipe sections in a machine of the type having an external mold and a rotary head adapted to form the interior surface or bore. Such machines have been provided further with arms which may be extended into the flaring ends of the sections to pack the concrete. Such a machine is described and illustrated in United States Patent No. 1,177,734, dated April 4, 1916, to Stewart and Schenk. The present invention comprises a machine of this type particularly adapted to pack the concrete or cement in the bell or flare of a pipe containing a metal reinforcement. As far as I am advised, the old forms of machines have not been capable of forming such pipe.

My objects are: first, to provide in such a machine packer arms adapted to extend into the flaring end or bell of a mold in the restricted space between the end form or pallet and reinforcement; second, to provide oscillating arms adapted upon their working strokes to direct the concrete outward into the bell of the pipe and between the reinforcement and the outer mold; third, to provide such a machine with means for properly centering the reinforcement in the walls of the pipe and, fourth, to provide improved operating mechanism for vertically oscillating packer arms. This invention also includes certain other novel features of construction which will be more fully pointed out in the following specification and claims.

In the accompanying drawings, Figure 1 is a fragmentary side elevation of a pipe forming machine, having my improvements thereon; Fig. 2 is a front elevation of the same; Fig. 3 is a front elevation showing mechanism for operating packer arms with the operating lever in raised position; Fig. 4 is a central vertical section through a typical mold and the former head having my improved packer arms thereon; Fig. 5 is a front elevation of the operating mechanism for said arms with the lever in lowered position; Fig. 6 is an end view of one of the packer arms; Fig. 7 is a perspective view of one of said arms and Fig. 8 is a horizontal section taken on the line 8—8 of Fig. 4.

Referring particularly to Figs. 4 and 8, my

invention is adapted for use on a machine of the type in which the outer surface of a pipe is formed by a mold 10 having a flaring portion 11. An inner mold or pallet 12 projects up within the portion 11, forming an annular recess within the same to receive concrete. The inner surface or bore of the pipe, indicated by the dotted line 13 in Fig. 4, is formed by a cylindrical head 14, which is rotated and drawn longitudinally through the pipe by a shaft 15. A wire reinforcement consisting of circular wires 16 and transverse connecting wires 17 is arranged to be embedded in the concrete of the finished pipe, being disposed in spaced relation to the mold 10. This reinforcement fits freely within the mold 10 and extends into the bell-shaped portion 11 thereof. The former head 14 has a flat top 18 upon which the concrete is deposited and from this top surface a pair of blades or cheek pieces 19 project upward to direct the concrete to the outer periphery of the head. These cheek pieces also assist in packing and smoothing the material in the formation of the bore of the pipe.

It will be evident that the location of the reinforcement wires 16 and 17 within the flaring portion of the mold leaves an extremely restricted space for the operation of mechanism for packing the bell. To pack the concrete outward and downward in the flaring end of the mold, I provide a pair of packer arms 20, which are pivoted upon pins 21 in recesses at opposite sides of the head 14. As shown in Figs. 6 and 7, the packer arms extend obliquely upward from the pivot pin 21 and have offset portions 22, formed to clear the upper extremity of the pallet 12. At its outer or operating end, each arm 20 has a rearwardly and downwardly extending portion 23 to which is bolted a shoe having two trowelling surfaces, viz, a bottom trowelling surface 25 and an outer side surface 26, adapted to direct the concrete outward between the wires of the reinforcement and toward the bell 11 of the mold. Disposed on the offset portion 22 of each arm 20, is a bearing 27, arranged to receive an end of an operating rod 28. The rod 28 has a laterally bent portion extending through the bearing 27 and its extremity is threaded to receive a nut 29.

The shaft 15 extends vertically and is movable longitudinally and revolvable in bearings 31 and 32 supported upon the frame of the machine. Another bearing 30 is slidable longitudinally with the shaft 15 as hereinafter

described. The upper ends of the rods 28 are secured to suitable ears projecting from a collar 33 upon the shaft 15, said shaft passing freely through the collar. Beneath the collar 33 is a clamp 34, which is fixed upon the shaft and projects at opposite sides to form bearings for the rods 28. To maintain the collar 33 in spaced relation to the clamp 34, I provide a coiled spring 35, which encircles said shaft and abuts at its upper and lower ends respectively against said collar and clamp. A portion of the collar 33, which projects upward along the shaft 15 is formed with an annular groove for a ring 36. This ring is connected by a link 37 to a lever 38 for operating the packer arms. The fulcrum for the lever 38 consists of a pivot pin 39, supported upon a vertical rod 40. A transverse frame member 41 supports the rod 40 and is formed with an opening in which said rod is slidable. Springs 42 and 43 are mounted upon the rod 40, below and above the frame member 41 respectively, to form resilient retaining means for said rod. A detent 44 projects downward adjacent to the lever 38 to support said lever in elevated position. This detent is secured to the frame member 41 and has a projecting lug 45 adapted to extend beneath the lever 38 when said lever is raised.

Any suitable mechanism for rotating the shaft 15 and for imparting longitudinal movement thereto may be provided, but the mechanism herein shown is similar to that described in the patent to Stewart and Schenk above referred to. This mechanism, as far as it is pertinent to the present invention, may be described as follows. Between the bearings 31 and 32, the shaft 15 has keyed thereto a pulley 46, adapted to be rotated by a belt 47. The belt 47 may be driven by a suitable electric motor under control of a clutch. It will be understood that although the shaft 15 is keyed to the pulley 46 it is free to move longitudinally therethrough. To move the shaft 15 longitudinally, a collar 48 may be fixed thereon above the bearing 30, and the latter bearing is connected to the lower end of a cable 49, which passes over a guide pulley 50 and is arranged to be wound upon a drum 51 upon a shaft 52. A worm wheel and worm are provided for turning the shaft 52 and the worm may be driven by an electric motor through any suitable or well known power transmitting mechanism, whereby the direction of rotation of the worm may be reversed. To guide the shaft 15 in its longitudinal movement, I provide a pair of large rods 53, which are rigidly supported upon the frame in brackets 54. The bearing 30 has laterally projecting arms connecting it to bearings 55 slidable upon the rods 53.

At the base of the frame, a suitable support 56 is provided for the pallet 12 and mold 10. This support may be supplied with pin-tiles 57 to removably engage the pallet 12. To

hold the mold 10 down and properly center it relative to the shaft 15, a table 58 is mounted above the mold and arranged for vertical movement upon the guide rods 53. Smaller rods 59 extend vertically adjacent to the 70 guide rods 53, the lower ends of the rods 59 being secured to the table 58 and their upper ends being slidable in suitable bearings 60 which project from a pair of the supports 54. Movement of the rods 59 in the 75 bearings 60 is limited by collars 61 and 62, which are rigidly secured to said rods below and above the bearings 60 respectively. The collars 61 project into the path of the bearings 55. Thus, in the operation of the machine when the bearings 55 and 30 are carried upward with the shaft 15 and approach the upper extremity of their movement, the bearings 55 strike the collars 61 and raise the rods 59 together with the table 58. 80 85

Operation.

To mount the mold in the machine, the pallet 12 is first placed upon the support 56 and then the reinforcement is supported upon the pallet, the lower ends of the longitudinal wires 17 resting thereon. Now the mold 10 is centered upon the pallet, as shown in Fig. 4, and the support 56 is placed in axial alignment with the shaft 15. Assuming that the head 14 is raised to its uppermost position, the bearings 55 would be in engagement with the collars 61 so that the table 58 is elevated free of the mold. Now the shaft 15 may be lowered by unwinding the cable 49 from the 100 drum 51. This lowers the table 58 upon the top of the mold 10 so as to retain said mold in properly centered position. Continued downward movement of the shaft carries the head 14 down through the central opening in the 105 pallet 12 until the upper surface 18 of the head is substantially flush with the upper extremity of said pallet.

During the downward movement of the shaft 15 and head 14, the arms 20 are retained in their raised position, indicated in dotted lines in Fig. 4. Thus, the lever 38 is raised and supported upon the detent 44 during the downward movement. Now assuming that the head 14 is in its lowest position, as shown 110 in Fig. 4, concrete sufficient to form the bell of the pipe may be admitted through the central opening in the table 58, whence it falls upon the surface 18 of the head 14. The shaft 15 and head 14 are now rotated in the direction 115 indicated by an arrow in Fig. 8, longitudinal movement of the shaft being arrested until the bell of the pipe is formed. The cheek pieces 19 throw the concrete beyond the outer periphery of the head 14, where it falls into the annular recess formed between the pallet 12 and flaring portion 11 of the mold. As the rotation of the head 14 continues, the lever 38 may be released from the detent 44 and manually oscillated about its horizontal pivot 120 125 130

This imparts reciprocating movement to the rods 28 and oscillating downward and outward movement to the arms 20 which pack the concrete firmly in the bell of the mold.

5 Simultaneously with this packing operation, the arms 20 center the reinforcement wires 16 and 17. Thus, if said reinforcement is not properly centered in the mold, the arms 20 in their rotation will move the wires to their positions equidistant from the mold. It will be noted that by reason of the location of the pivot pins 21 beneath the upper surface of the head and pallet, the arms 20 are directed outwardly as well as downwardly. This forces 10 the concrete out between the wires of the reinforcement and firmly packs it against the inner surface of the mold, as well as between the pallet and reinforcement. This arrangement also makes it possible to operate the packer 15 arms in the restricted space between the reinforcement and outer extremity of the pallet 12. As the arms 20 are swung back or retracted from the annular recess in the bell, they are thus caused to clear the reinforcement.

25 The oscillating movement of the arms 20 is continued until the concrete becomes firmly packed in the bell, when it automatically forces the arms upward. My arrangement of 30 the spring 35 minimizes the work of oscillating the lever 38 because the weight of the parts, including the rods 28, arms 20 and lever 38 is offset by the spring, which tends to raise the lever. The springs 42 and 43 give a resiliency to the packing strokes, which insures 35 a substantially uniform packing of the bell, irrespective of the force of the manual stroke applied to the lever. The spring 42 further permits the arms 20 to retract in the event 40 that they strike an immovable obstacle on the packing stroke. The spring 43 also facilitates movement of the lever 38 into engagement with the detent 44 and minimizes the danger 45 of bending or breaking parts of the apparatus if the lever is moved upward with too great force.

50 After the bell has been packed, the arms 20 are retracted to their dotted line position, shown in Fig. 4 and the upward travel of the head simultaneous with the continued rotation thereof is started. Additional quantities of concrete are supplied from time to time as the pipe is formed, the cheek pieces 19 operating to feed the concrete outward and to 55 trowel the inner surface while the head finishes the trowelling operation. By these means, a smooth, uniform bore in the pipe is insured, while the cylindrical portion of the pipe is formed and the wires 16 and 17 are embedded therein. As the head 14 passes out 60 through the central opening in the table 58, the bearings 55 strike the collars 61 on the rods 59 and raise the table out of engagement with the mold. The pipe with its mold and 65 pallet, may now be removed from the support

56 and the mold stripped from the pipe in the usual manner.

Having described my invention what I claim as new and desire to protect by Letters Patent is:

70 1. The combination with an outer mold having a flaring lower end and an inner mold extending up into said end in spaced relation thereto, forming an annular recess to be packed with moldable material, an arm pivoted at a point below the upper extremity of said inner mold and arranged to be extended into said recess and means for operating said arm in an outward and downward direction to pack said material in said recess.

75 2. The combination with an outer mold having a flaring end and an inner mold extending into said end in spaced relation thereto, forming an annular recess to be packed with moldable material, an arm pivoted at a point longitudinally outward from the inner extremity of said inner mold and extending into said recess, means for rotating the free end of said arm in said recess and means for simultaneously oscillating said arm into and out of said recess.

80 3. The combination with an outer mold having a flaring end and an inner mold extending into said end in spaced relation thereto, forming an annular recess to be packed with moldable material, of an arm pivoted at a point longitudinally outward from the inner extremity of said inner mold, means for traversing the free end of said arm in said recess and means for simultaneously oscillating said arm into and out of said recess, said arm having an upwardly offset middle portion and an outer portion arranged to extend below the inner extremity of said inner mold.

85 100 105 4. The combination with an outer mold having a flaring end and an inner mold extending into said end in spaced relation thereto and forming an annular recess adapted to be packed with moldable material, said inner mold being formed with a central opening, a rotary support closing said opening, a packer arm carried by said support and having a pivot positioned longitudinally outward from the inner surface of said support, said arm having a portion formed to project into said annular recess, a trowelling member on the free end of said arm, means for rotating said support and means for oscillating said arm to pack said material in an outward direction in said recess.

110 115 120 125 130 5. The combination with an outer mold having a flaring end and an inner mold extending into said end in spaced relation thereto, forming an annular recess adapted to be filled with moldable material, said inner mold being formed with a central opening, a rotary support revoluble in said opening, the inner surface of said support being substantially flush with the inner extremity of

said inner mold, a packer arm pivoted upon said support and having its pivot positioned longitudinally outward from the inner surface of said support, said arm having an outer portion formed to extend within said annular recess, trowelling surfaces formed on the outer end of said arm, means for rotating said support and means for oscillating said arm to pack said material in an outward direction in said recess.

6. The combination with a cylindrical outer mold having a flaring, lower end and an inner mold extending up into said end in spaced relation thereto and forming an annular recess adapted to be filled with moldable material, said inner mold being formed with a central opening, a rotary support adapted to close said opening and arranged to be positioned with its inner surface substantially flush with the inner extremity of said inner mold, a packer arm pivoted upon said support with its pivot positioned below the inner surface of said support, said arm projecting substantially radially, a downwardly and rearwardly projecting free end arranged to extend within said annular recess, trowelling surfaces formed on the outer and normally lower extremities of said end of said arm, means for rotating said support and means for oscillating said arm to pack said material in an outward direction in said recess.

7. The combination with a mold having a flaring end and an annular recess in said end to be packed with moldable material, an arm pivoted and arranged to extend into said annular recess for packing material therein and means for oscillating said arm comprising a lever operatively connected with said arm, a movable support for said lever, a fixed support adjacent to said movable support and resilient means interposed between said fixed and movable supports to impart resiliency to the packing stroke of said arm.

45 8. The combination with a mold having a flaring end and an annular recess in said end to be packed with moldable material, an arm pivoted and arranged to extend into said annular recess for packing material therein, a shaft extending into said mold and connected to said arm for rotating the same in said recess and means for oscillating said arm comprising a lever operatively connected with said arm, a collar slidable on said shaft and operatively connected to said lever, a fixed support adjacent to said collar and a spring

interposed between said fixed support and collar to resiliently support said packer arm and lever.

9. The combination with a mold having a flaring end and an annular recess to be packed with moldable material, an element adapted to be extended into said mold and to be rotated therein, an arm pivotally carried by said element and formed to extend into said annular recess to pack said material therein, a shaft for rotating said element projecting from said mold, a collar on said shaft slideable longitudinally thereon, means operatively connecting said collar with said arm for oscillating said arm, a lever connected with said collar to impart reciprocating movement thereto along said shaft, a pivot for said lever arranged for movement substantially longitudinally of said shaft and resilient means supporting said pivot.

10. The combination in a machine for forming reinforced pipe, of an outer mold having a flaring end and an inner mold extending into said end in spaced relation thereto, forming an annular recess to be packed with moldable material, a reinforcement to be embedded in the pipe disposed in spaced relation to the inner surface of said mold, a rotary element in said mold, a pair of arms pivoted on opposite sides of said element, said arms being adapted to be extended into said recess between said reinforcement and inner mold to engage and center said reinforcement in said mold and means for oscillating said arms in an outward direction to pack concrete between said reinforcement and mold.

11. The combination in a machine for forming reinforced pipe, of an outer mold having a flaring end and an inner mold extending into said end in spaced relation thereto, forming an annular recess to be packed with moldable material, a wire reinforcement to be embedded, disposed in spaced relation to the inner surface of said mold, a rotary element in said mold, a pair of arms pivoted on said element and having pivots located longitudinally outward from the inner extremity of said inner mold, said arms being adapted to be extended into said recess to engage and center said reinforcement in said mold and means for oscillating said arms into and out of said recess.

In testimony whereof, I have hereunto signed my name to this specification.

ALFRED W. SCHULTZ.
